VARIABLE AUTOMATIC CLEARANCE POCKET

Charles O. Meyers, Bartlesville, Okla., assignor
to Phillips Petroleum Company, a corporation
of Delaware

Application December 19, 1946, Serial No. 717,263

5 Claims. (Cl. 230—237)

1

This invention relates to reciprocating compressors. In one of its more specific aspects it relates to a variable automatic clearance pocket for use with reciprocating compressors.

The petroleum industry in general, and specifically the natural gas and gasoline industry, use large numbers of reciprocating or piston type compressors. This latter industry uses these compressors for, among other things, compressing hydrocarbon gases prior to extraction of condensable or gasoline boiling range hydrocarbons.

Power units for operating such gas compressors may be selected to operate at or very nearly capacity for maximum operating efficiency and for savings in capital investment. And further, these power units may be selected to operate at capacity for compressing gas from an available intake pressure to a desired outlet pressure. For example, a compressor installation may be designed for compressing gas from a newly drilled field, from which a small amount of gas may be available for compression at a relatively low pressure. After the field is fully developed or the gas/oil ratio increases, the pressure of the gas frequently starts to increase. This increase in field pressure often effects an increase in pressure in the suction manifold of a compressor system. Such a pressure rise means that the compressor cylinders will receive an increased quantity of gas on each intake stroke. If the compressor is discharging against a constant pressure, the compression of this increased quantity of gas will increase the horsepower demand on the power unit which was originally operating at its full rated power output. This increased horsepower demand will therefore overload the power unit.

Another compressor installation may be designed for compressing gas from a newly drilled field which is in a flush period of production. During this initial period the gas pressure available in the suction manifold of the compressor installation may be relatively high. However, it is known that this gas pressure will decline and that the field may subsequently produce at lower pressures and over a long period of time.

Still other compressor installations may receive gas at a pressure which may change from day to day, or even from hour to hour. Most oil producing states, such as Texas, establish monthly "allowable crude oil production" for producing wells. Under such circumstances, some producers frequently pump wells continuously or at least eight hours a day, for the first

part of the month or until the allowable oil has been produced and then the well is shut down during the remainder of the month. Such operations make for variable production gas pressure.

For any type of gas production compressor cylinders are usually selected so that the power units will be fully loaded when the compressors are operating at the expected lower inlet pressure. Thus it is necessary to adjust the volumetric efficiency of the compressor cylinders so as to load fully but not overload the power unit during higher pressure production periods.

Several methods have heretofore been available for solving such an engine overload problem; first, installation of a larger power engine; second, replacement of the compressor unit with one having a smaller cylinder; third, replacement of the original compressor cylinder and piston with a smaller cylinder and piston which procedure may sometimes be followed since many compressors are adapted for such alterations; and fourth, installations of external clearance pockets, a clearance pocket being defined as an attached gas receiving space in direct connection with the compressor cylinder such that there is an increase in residual gas volume at the end of the compression stroke. The first two of these methods involves considerable investment, while the third involves less, yet appreciable expense. The last method requires the least expenditure, but its range of application is somewhat limited.

Some attempts have been made to utilize on and off or manually adjustable clearance pockets to solve the above mentioned problem. Such clearance pockets offer only a partial solution to the problem since an operator must recognize the engine overload condition and then manually open one or more valves to one or more clearance pockets, and this operation to be effective must be done before an engine stalls when an increase in manifold gas pressure has overloaded the power unit. The reverse is also true, that is, an operator must observe by pressure gage or a recording chart when gas manifold pressure has decreased, then close off one or more clearance pockets to keep the engine operating at maximum efficiency.

An operator of a gas compression plant in which there are 12 to 15 or more compressors would frequently need a helper or two designated as "clearance pocket operators" in case gas manifold pressure fluctuates and manually operated pockets were used.

I have developed a variable and automatically operated clearance pocket for gas compressors operating under variable intake pressure conditions.

An object of my invention is to provide an automatically operable means for reducing the volumetric efficiency of gas compressors.

Another object of my invention is to provide a variable and automatically operable means for reducing the volumetric efficiency of gas compressors.

Still another object of my invention is to provide a variable and automatically operable means for reducing the volumetric efficiency of gas compressors when compressor suction pressure has become increased, in order to maintain the compression load within the rated power output of the prime mover driving such compressors.

Many other objects and advantages of my invention will be apparent to those skilled in the art from a careful study of the following disclosure and attached drawing which respectively describes and illustrates a preferred embodiment of my invention.

The figure illustrates diagrammatically, partly in cross section and partly in elevation, a preferred form of my automatic and variable clearance pocket attached to a compressor cylinder.

Referring now to the drawing, a compressor cylinder 1 is fitted with a gas inlet pipe 2 and a compressed gas outlet pipe 3. A second connection 4 is provided for attachment of my variable automatic clearance pocket mechanism 5.

The gas inlet pipe 2 is intended to conduct gas to be compressed from a suction manifold line (not shown) to a compressor cylinder. Pipe 3 conducts compressed gas from the compressor cylinder 1 to a control chamber 6 of the clearance pocket mechanism. This control chamber discharges the compressed gas through a pipe 7 which in turn conducts the compressed gas to a storage tank, to a process step or to other disposal, as desired, and not shown on the drawing for purposes of simplicity.

My clearance pocket mechanism is composed of two main parts, the control chamber 6 and a variable clearance section 8.

The variable clearance section 8 is composed of a cylindrical wall 9, the interior surface of which is machined so as to accommodate and permit movement of a carefully fitted piston 12. A space or volume 10 directly under the piston 12 is the variable volume clearance space. This cylindrical wall 8 has a side outlet with a flange 11 for connection to flange 4 of the compressor cylinder. The bottom end of the wall 8 terminates in a flange 13 to which may be attached a cover plate 14, the connection being made gas tight by use of a paper gasket, not shown. Flanges 4 and 11 of course are fitted with gaskets also.

Into the upper end of the piston 12 is inserted by screw threads or other means a connecting rod 15 to the top end of which is attached a conical shaped bob 16. This bob 16 may be made integral with the rod 15, if desired or may be attached by threads or other means. On account of rapid movement and vibration during operation it may be preferable to make the bob and rod as one unit.

The cylindrical wall 9 is intended to act as a cylinder in which the piston 12 fitted with one or more piston rings, may move freely.

The upper end of the cylindrical wall 9 has a closure member 17 which in turn is fitted with

a packing gland 18 in such a manner that some oil 20 in the space between the piston and the closure member 17 cannot leak around the connecting rod 15. A coil spring 19 is attached to the underside of the closure member 17 and to the upper side of the piston 12 or to the connecting rod 15 at a point near the upper surface of the piston. This spring is intended merely to carry the dead weight of the bob, piston, connecting rod and the weight of the oil 20.

A reservoir 25 also contains oil 20 which may pass into or out of the cylinder by way of a tube 26 as the piston 12 falls or rises.

The control chamber 6 is tapered as shown so that the higher the bob 16 is in the tapered chamber the greater is the area of the annular space between the periphery of the base of the bob 16 and the side wall of the chamber. The upper end of the chamber 6 is made with an outlet carrying a flange 22 to which a flange of the discharge pipe 7 may be connected.

My clearance pocket apparatus may be used on substantially any size compressor cylinder where clearance pockets are needed. The sizes of the pocket cylinder, piston and bob portions may be the same for some different sizes of compressor cylinders, and the control chamber member 6 may be varied in size to suit requirements. That is, a 20 inch diameter compressor cylinder will require a larger control section member 6 than will an 18 inch diameter cylinder of the same stroke. The 20 inch cylinder will pass a larger volume of gas than an 18 inch cylinder while clearance volume requirements will be of the same order of magnitude and the volume adjustments for both cylinders may be accomplished with the use of the same size clearance section 5. By providing a flange 24 at the contact between the control section 6 and the piston section 8 different sizes of control sections 6 may be used with one piston section.

A tube 26 connects the bottom of an oil reservoir 25 with the volume between the piston 12 and the cylinder closure member 17. This volume, tube 26 and a portion of the reservoir 25 contain the oil 20. A tube 27 establishes fluid communication from the space above the oil in reservoir 25 to the clearance volume 10.

In the operation of my variable automatic clearance pocket, a gas to be compressed may be conveyed to the compressor cylinder at 2 pounds per square inch gage pressure and compressed to say 50 pounds per square inch gage pressure. Many gas compressors have spring loaded discharge valves or such other type of discharge valve that when a predetermined pressure of the gas is reached the valve will open and the remainder of the compression stroke will then serve to discharge the compressed gas. Under such conditions the engine driving the compressor may be operating at capacity.

When the pressure of the gas to be compressed is increased to say 5 pounds per square inch more power is required to compress gas from this pressure to 50 pounds than from 2 pounds to 50 pounds. Thus the power engine will be overloaded.

During normal compressor operation the compressed gas passes through the compressor discharge pipe 3 and passes into and through the control section 6 of my apparatus. The surface area of the underside of the bob 16 and the area of the annular space between the bob 16 and the wall of the control chamber 6 are so chosen that when this normal volume of gas passes by

the bob 16, the bob will not be or substantially will not be raised. But when the inlet gas pressure has been raised to say 5 pounds or more, more gas enters the compression cylinder on an intake stroke and therefore more gas will be discharged at 50 pounds' pressure during the compression stroke.

When this increased volume of gas is discharged from the compressor cylinder and passes through the annular space between bob 16 and the wall of chamber 6 the bob 16 is exposed to a pressure differential for a longer period of time than when compressing the one to two pound gas and this pressure differential acting on bob 16 for a longer period of time will move the bob a greater distance in the downstream direction than when the bob is exposed to the same pressure differential for a shorter period of time.

When the bob is raised the piston 12 is raised also and the volume 16, more accurately called the "clearance volume," increases and this increases in clearance volume unloads the driving engine since it permits discharge of a smaller volume of compressed gas from the cylinder to the compressor discharge pipe. The decrease in volume of the discharged gas is accordingly proportional to the increase in clearance volume 16 caused by the rise of the piston 12.

The tube 27 permits pressure from within the clearance chamber 10 to be communicated to the oil 20. Thus any pressure acting on the bottom side of the piston 12 is also acting on the top side of the piston 12, or in other words the piston is not moved by the pressure of gas in the clearance volume 16. The only force acting to move the piston is the passage of gas around the bob 16.

The spring 19 need not be especially "strong" since it is used merely to support the weight of the bob-connecting rod-piston assembly and to assist in returning the bob to its original and normal position after abnormal inlet gas pressure has ceased to exist and the volume of gas passing the bob at each discharge stroke is the normal intended volume.

The oil 20 serves as a pulsation dampener. Tube 26 is sized so as to prevent the rapid flow or surging of oil from the cylinder to oil reservoir 25. In some instances it may be desirable to place a choke or orifice in tube 26 to control the flow of oil. Since the oil is relatively viscous any movements of the bob are damped and the overall result is during times of 2-pound inlet gas pressure the bob remains substantially at its initial position, and during times when the inlet gas pressure is 5 pounds (or any other pressure greater than 2 pounds) the bob rises and remains substantially fixed at its new position until the inlet gas pressure changes. If the gas pressure further increases, the bob will rise further or if the inlet gas pressure drops the bob will fall also to decrease the clearance volume. In this manner the load on the engine driving a compressor equipped with the clearance pocket of my invention will remain remarkably constant.

The clearance pocket assembly described herein is for one end of a compressor cylinder, and if the compressor is "double acting," a similar apparatus may be installed on the other end of the cylinder. It is preferable to have clearance pocket operation on both ends of such a cylinder, otherwise an unbalanced operation results and such unbalanced operation is not conducive to longer compressor life.

The diameter of the piston 12, and the diameter and the conical pitch of the walls of the control chamber 6 relative to the diameter of the bob 16 may be determined for each size of compressor cylinder taking further into consideration the compressor inlet and outlet pressures. The diameter of the piston 12 and distance of its upward movement provides the increase in clearance volume. The slope or conical pitch, among other factors, determines the distance the bob rises for the passage of a given volume of gases through a given central chamber. The smaller the conical pitch, the greater will be the bob movement for the passage of a given volume of gas.

The oil used in the pulsation chamber 25 may be a lubricating oil, as mentioned hereinbefore, and if a lubricating oil it should possess a relatively high viscosity index. In place of oil, glycerin or other type of hydraulic fluid may be used; but whatever fluid is used, it should exhibit relatively constant characteristics as to viscosity, etc., at atmospheric conditions, winter or summer, as well as at compressor operating temperatures. This fluid should not form sludge nor wax to plug the tube 26 or to interfere with the movement of piston 12 against the wall of the clearance chamber or with the movement of the rod 15 in the packing gland 18.

If desired and to save first cost, the control chamber may be made relatively small in comparison to the size of the bob 16 and through this small control chamber then may be passed a constant fraction of the compressor output. For example, if the compressor discharge pipe is a .4 inch diameter pipe, a .2 inch take-off pipe may be installed and from the ratio of the cross sectional areas of these two pipes, the smaller should permit flow of about one-fourth the volume of compressed gas all of which would otherwise pass through the .4 inch pipe. This smaller volume of compressed gas then may be passed through a relatively small control chamber to operate a clearance pocket as hereinabove described.

Example.

A compressor cylinder of size 18 inches by 20 inches is compressing gas at the rate of 1,735 M. C. F. D. (thousand cubic feet per day) from an intake pressure of 2 pounds per square inch gage to a discharge pressure of 43 pounds per square inch gage. Loading is approximately 125 brake horsepower. The cylinder clearance is 3.87% atmospheric pressure 14.4 pounds per square inch and the "n" value of the gas is 1.26. The intake pressure is suddenly increased to 5 pounds' gage pressure thereby throwing a compression load of 138 horsepower on the power unit. At this increased intake pressure, the compressor passes gas at the rate of 2,070 M. C. F. D. This increased flow of gas actuates the controlling mechanism and increases the clearance volume to 8%, thereby decreasing the gas flow and unloading the engine to its normal 125 horsepower loading. At this 8% clearance and 5 pounds' inlet gage pressure 1,950 M. C. F. D. of gas is passed.

The clearance volume remains at 8% as long as the intake pressure is 5 pounds. Upon decrease of intake pressure to 2 pounds, less gas is passed and the apparatus actuates to decrease the clearance volume to 3.87% with an engine loading of 125 brake horsepower.

Materials for use in the construction of my

variable automatic clearance pocket may be selected from among those commercially available. No special material is needed.

It will be obvious to those skilled in the art that many variations and modifications of my clearance pocket mechanism, such as, dimensions or mechanical parts, the slope or angle of the side wall of the control section, etc., may be made and yet remain within the intended spirit and scope of my invention.

Having disclosed my invention, I claim:

1. A variable, automatic clearance pocket for use in conjunction with reciprocating gas compressors comprising a cylinder adapted to be attached at one end to a compressor cylinder, the first mentioned cylinder fitted with a piston, means to equalize pressure on both sides of said piston, and means attached to said piston and extending beyond the other end of its containing cylinder for moving said piston, a housing means surrounding the extended portion of said piston moving means, a further means attached to said housing means and to said gas compressor cylinder and adapted to convey compressed gas from said compressor cylinder into said housing means, said extended portion of said piston moving means adapted to move said piston in response to the flow of gas through said housing means.

2. A variable, automatic clearance pocket for use in conjunction with reciprocating gas compressors, comprising a cylinder adapted to be attached at one end to a compressor cylinder having an intake and an outlet, the first mentioned cylinder fitted with a piston, means attached to said piston and extending beyond the other end of its containing cylinder for moving said piston, and means for equalizing pressure on both sides of said piston, a housing means surrounding the extended portion of said piston moving means, a further means attached to said housing means and to said gas compressor cylinder and adapted to convey compressed gas from said compressor cylinder into said housing means, said extended portion of said piston moving means adapted to move said piston in response to the flow of gas through said housing means.

3. The variable, automatic clearance pocket of claim 2 wherein said means for equalizing pressure on both sides of said piston comprises means for communicating fluid pressure from one side of said piston to the other side.

4. A cylinder for a reciprocating gas compressor having an intake and an outlet, and means for varying the effective clearance volume of the cylinder, comprising in combination a clearance volume chamber in communication at one end with the head of the compressor cylinder, the clearance volume chamber being fitted with a piston to vary the effective volume of said chamber, a gas flow bob in said outlet and attached to said piston and being responsive to the volume of discharge through said outlet to position the piston so that the effective volume of the clearance chamber will be varied directly as the volume of said discharge.

5. A cylinder for a reciprocating gas compressor having an intake and an outlet, and means for varying the effective clearance volume of the cylinder, comprising in combination a clearance volume chamber in communication at one end with the head of the compressor cylinder, the clearance volume chamber being fitted with a piston to vary the effective volume of said chamber, means to equalize pressure on opposite faces of said piston, a gas flow bob in said outlet and attached to said piston and responsive to the volume of discharge through said outlet to position said piston so that the effective volume of the clearance chamber will be varied directly as the volume of said discharge.
